(57) CLAIM

The ornamental design for a water cooler, as shown and described.

DESCRIPTION

FIG. 1 is a perspective view showing one embodiment of my water cooler;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a perspective view thereof with a single cup holder in broken line;

FIG. 8 is a perspective view thereof with a dual cup holder in broken line;

FIG. 9 is a perspective view thereof with the doors open in broken line;

FIG. 10 is a perspective view of a water cooler showing my new design; and,

FIG. 11 is a perspective view of the first embodiment with a shortened base in broken line.

The broken lines in the drawings are for illustrative purposes only and form no part of the claimed design.
